UNITED STATES PATENT OFFICE.

JOHN W. CLOUD, OF ALTOONA, PENNSYLVANIA.

RAILWAY SIGNAL-LANTERN.

SPECIFICATION forming part of Letters Patent No. 355,438, dated January 4, 1887.

Application filed April 29, 1886. Serial No. 200,549. (No model.)

To all whom it may concern:

Be it known that I, JOHN W. CLOUD, of Altoona, Blair county, and State of Pennsylvania, have invented a new and useful Improvement 5 in Railway Signal-Lanterns, of which the following is a true and exact description, reference being had to the accompanying drawings, which form a part of this specification.

10 My invention relates to the construction of railway signal-lanterns, especially such as are attached to the outside of cars or locomotives and are exposed to violent drafts and to dust and grit; and its object is to construct the lantern so that it may be readily turned on its base to display lights of different colors without leaving any cracks or orifices through which air can enter the lantern except the regular air-supply conduits, and generally to 15 improve, strengthen, and cheapen the lantern.

Reference being now had to the drawings, which show a lantern made, in accordance with my invention, Figure 1 is a perspective view of my improved lantern. Fig. 2 is a 25 sectional elevation of the lantern on the line xx of Fig. 3. Fig. 3 is a sectional view on the line yy of Fig. 2, and Fig. 4 is a sectional view on the line zz of Fig. 2.

A is the frame or body of the lantern; B, 30 an annular metal ring, made perfectly smooth and cylindrical inside, and having an annular flange, B', formed on its outer surface, to which the lantern-frame A is securely attached. The ring B, as shown, has also a box, 35 B'', cast or formed with it.

C is the bottom or base of the lantern, at the top of which there is, first, a flat annular surface, C', upon which the ring B can rest, and then a cylindrical projection, C'', forming a 40 close fit and bearing for the ring, and at about half the height of the ring B this cylinder terminates in the inwardly-extending flange C'.

D is a bracket or arm attached to the lantern-bottom C, and by which the lantern is 45 secured to the car, engine, or other place where it is wanted for use.

E is a spring-catch secured to the ring B, and adapted to engage with retaining devices formed in or secured to the lantern-base. Its 50 object is to provide a means of holding the lantern in any desired position corresponding to the lenses used. As shown, the catch E is

secured in the box B'', and engages with holes e in the cylindrical projection C'.

F is a metal plate formed to fit upon the 55 flange C', to which it is secured by screws, rivets, or other devices f. It is continued upward in the form of a cylinder, F', of the same diameter as C', and to a height which will bring it to or a little above the top of the ring B, and it is then turned outward, forming the flat annular flange F''.

G is a screen and reflector of sufficient size to sufficiently screen one of the two lantern-lenses from the light, its concave inner surface 65 being bright, so that it will strengthen the beam of light thrown through the open lens. This screen must be secured to the stationary part or base of the lantern, and should preferably be inside of the frame, as shown, though 70 it will of course be operative both as a screen and reflector if secured to the outside of the base. As shown, it is securely and permanently attached to the plate F.

H is the lamp, having a handle, H'.

I are the lenses, which are white or colored, as desired.

J is the top of the lantern, which is hinged at K, and has a clasp, L, for securing it when closed.

M is a handle, and O the chimney and draft-cowl.

N N are the conduits through which air is supplied for the lamp. They have openings n n at the top to admit the air and openings P 85 at the bottom, through which the air escapes into the lantern after passing vertically downward.

In putting my improved lantern together the body A may first be secured to the ring B, 90 which is then slipped over the cylinder C' and allowed to rest upon the annular surface C''. The plate F, with its attached screen G, is then inserted in the lantern, its cylinder F' filling the upper part of the ring B, and the flange C'' 95 and plate F are then secured together and in proper position by the fastenings f.

The ring B and the lantern-body secured to it will turn freely upon the cylinders C' and F', which at the same time, together with the 100 flanges C' and F'', effectively secure it against displacement or tipping and unite the body and bottom of the lantern securely together, the joint being so close and of so tortuous a

form that no appreciable amount of air can enter the lantern through it.

As shown in the drawings, the bottom C is made of sheet metal, which I prefer to use, 5 though, if desired, the bottom C and plate F may of course be cast and their cylindrical portions turned to the proper dimensions and smoothness to form a neat-fitting bearing for the ring B.

10 In the foregoing description I have, to make it easy to follow it on the drawings, spoken of the different parts as having the relative dimensions and projections there shown; but in many instances these are by no means essential. Thus the bearing-surface for the ring B, as shown, consists of the two cylindrical projections C² and F², of about equal size; but it is obvious that either of these may be enlarged at the expense of the other and to such an extent that the whole cylindrical part of the bearing may be made up of either the one or the other. If the cylinder C² is enlarged to this extent, the only essential part of the retaining-plate F F' F² will be the flange F², between which and the flange C² the ring B is held.

Having now described my invention, what I claim as new, and desire to secure by Letters Patent, is—

30 1. In a signal-lantern, substantially as described, the combination of the lantern-body secured to an annular ring, a base having an upwardly - extending cylindrical projection forming a bearing for said ring, a retaining-

plate adapted to be secured to the base and hold the ring in place upon its bearing-cylinder, and a catch or stop whereby the lantern may be retained in the desired angular position upon its base, substantially as and for the purpose specified.

2. In a signal-lantern, substantially as described, the combination of the lantern-body secured to an annular ring, a base having an upwardly - extending cylindrical projection forming a bearing for said ring, a retaining-plate adapted to be secured to the base and hold the ring in place upon its bearing-cylinder, a screen secured to the base and adapted to close one of the lantern-lenses, and a catch or stop whereby the lantern may be retained in the desired angular position upon its base, substantially as and for the purpose specified.

3. In a signal-lantern, substantially as described, the combination of the annular ring B, having a flange, B', to which the lantern-body is secured, the base C, having a cylindrical projection, C², forming a bearing for the ring B, the cylindrical flanged plate F F' F², forming the continuation of the bearing for ring B, and also a retaining device to secure it to the base, the screen G, secured to the plate F, and a catch to hold the lantern in position, all substantially as and for the purpose specified.

JNO. W. CLOUD.
